UNITED STATES PATENT OFFICE.

AMANDUS KLITSCHE, OF CHICAGO, ILLINOIS, ASSIGNOR TO FREDERICK POST COMPANY,
OF CHICAGO, ILLINOIS, A CORPORATION OF ILLINOIS.

VERTICAL-FILING CABINET.

1,170,975.

Specification of Letters Patent.

Patented Feb. 8, 1916.

Application filed November 4, 1912. Serial No. 729,354.

To all whom it may concern:

Be it known that I, AMANDUS KLITSCHE, a citizen of the United States, and a resident of Chicago, county of Cook, and State of Illinois, have invented certain new and useful Improvements in Vertical-Filing Cabinets, of which the following is a full, clear, and exact description.

The invention relates to vertical filing cabinets and seeks to provide a simple and effective construction wherein drawings or the like can be conveniently filed.

The invention consists in the features of improvement hereinafter set forth, illustrated in the preferred form in the accompanying drawings and more particularly pointed out in the appended claims.

In the drawings, Figure 1 is a perspective view of the improved cabinet with the front and top cover in open position. Fig. 2 is a partial vertical section taken on the line 2—2 of Fig. 3, with the front and top cover shown in closed position. Fig. 3 is a partial plan view with the front in closed position and the top cover removed. Fig. 4 is a view similar to Fig. 2, showing the front and top cover in open position.

The body of the improved cabinet comprises a rear wall 1, a bottom 2 and ends 3 secured together in suitable manner and the cabinet is provided with a swinging front 4 which is hinged thereto at its lower edge. Preferably, the front is provided with edge flanges 5 which are arranged to overlap the front edges of the ends 3 when the front is in closed position, as shown in Fig. 3. The front is adapted to be held in closed position in any suitable manner. In the form shown, it is provided at its upper end portions with sliding, spring-held catches 6 which are arranged to engage seats 7 in the upper front portions of the ends 3. A handle 8 at the upper central portion of the front is connected to the catches 6 in any suitable manner to withdraw the same from the seats 7, so that the front may be open. In the construction shown, the front 4 is adapted to be sustained in its full open, inclined position by chains 9 which extend between the same and the rear wall 1 of the cabinet. The cabinet is preferably provided with a top cover 10 hinged to the rear wall thereof and adapted to be held in open position by a pair of pivoted or folding links 11 extend-

ing between the cover and one of the ends 3 of the cabinet.

The drawings or other papers to be filed in the cabinet are secured at their upper edges by clamps 12' or in any other suitable manner, to a series of filing rods 12 and the projecting ends of the filing rods are sustained within the cabinet upon co-operating supports fixed to the body of the cabinet and to the swinging front thereof. In the preferred form shown, the supports comprise pairs of overlapping angle brackets 13 and 14 fixed respectively to the upper end portions of the rear wall 1 and the front 4.

The rear brackets 13 project forwardly from the rear wall 1 and are spaced from the end walls of the cabinet. The brackets 14 project rearwardly from the front 4 and are adapted to pass between the ends 3 of the cabinet and the brackets 13 as the front is opened and closed. The brackets 13 are provided at their upper portions with supporting ledges 15, and the front brackets 14 are provided with co-operating supporting ledges 16 which, when the front is closed, are arranged beside and in horizontal alignment with the supporting ledges 15. Each of the brackets 14 is also provided with a flange 17 which extends over the supporting ledge 16 and forms therewith a horizontal extending slot 18 for receiving the ends of the filing rods 12. Preferably, as shown, the slot 18 is closed at the outer side face of each of the brackets 14.

When the front is in closed position, the projecting ends of the filing rods extend across the supporting ledges 15 of the rear brackets and into the slots 18 between the supporting ledges 16 and flanges 17 of the front brackets. These rod engaging parts are slightly curved, being concentric with the hinges at the lower edge of the swinging front 4 so that the slotted front brackets 14 will properly engage the ends of the rods as the front is opened and closed.

In using the filing cabinet, the top cover 9 is opened and the drawings in front of the one to be inspected are drawn forwardly with the swinging front, as shown in Figs. 1 and 4. Part of the drawings are then supported upon the rear brackets 13 and the remainder on the front brackets 14. To prevent the accidental displacement of any of

the drawings on the rear brackets 13; the latter are provided at their upper front ends with depressible, spring-held stop pins 19 arranged within sockets 19' at their ends. 5
5 When the front is closed, the ends of the filing rods carried thereby are shifted onto the rear supporting brackets 13, depressing the spring-held stop pins 19. At the same time, the ledges and the flanges 16 and 17 10 of the front slotted brackets properly re-engage the ends of the filing rods which have remained upon the rear brackets. By arranging the front brackets between the rear brackets and the end walls, and providing the front brackets with flanges arranged to extend over the rods, the filing rods and drawings carried thereby, which are shifted outwardly with the swinging front, are securely held against displacement 15 and are properly returned to position in the cabinet when the front is closed.

For convenience in selecting the drawing to be inspected, the filing rods or the clamps may be provided, if desired, with index tabs. In the construction shown, the top cover is provided on its lower face with ribs 20 having slots 21 therein for receiving index cards.

It is obvious that changes may be made in 30 the details set forth without departure from the essentials of the invention as defined in the claims.

I claim as my invention:—

1. A vertical filing cabinet provided with 35 a swinging front, said cabinet and said front having coöperating ledges in horizontal alinement for supporting filing rods, and said swinging front having a flange arranged to extend over the filing rods to 40 maintain said rods in horizontal alinement.

2. The combination with a filing cabinet, of a swinging front hinged thereto at its lower edge, said cabinet and said front being provided at their upper end portions 45 with pairs of coöperating curved ledges for supporting filing rods, said ledges being arranged side by side in horizontal alinement when said front is closed and said front having flanges arranged to extend over the

ends of the filing rods to maintain said rods 50 in horizontal alinement.

3. The combination with a filing cabinet, of a swinging front hinged thereto at its lower edge, said cabinet and said front being provided at their upper end portions 55 with pairs of coöperating curved ledges for supporting filing rods, said ledges being arranged side by side in horizontal alinement when said front is closed and said front having flanges arranged to extend over the 60 ends of the filing rods to maintain said rods in horizontal alinement, and depressible spring held stop pins at the forward ends of the ledges of said cabinet.

4. A vertical filing cabinet provided with 65 a front hinged thereto at its lower edge, forwardly projecting supporting brackets fixed to the upper portion of the rear wall of said cabinet adjacent the ends thereof, and coöperating rearwardly projecting 70 brackets secured to said front and arranged to pass between said rear brackets and the end walls of said cabinet, said brackets having similarly curved supporting ledges for filing rods arranged in horizontal alinement when said front is closed, said front brackets having flanges above the supporting ledges thereof and arranged to extend over the ends of the filing rods, and depressible spring held stop pins at the forward ends of the supporting ledges of said 75 rear brackets.

5. A vertical filing cabinet provided with a swinging front, forwardly projecting curved supports for filing rods fixed to the 80 upper portion of the rear wall of the cabinet adjacent its ends, and similarly curved rearwardly projecting supports for the filing rods fixed to said front and arranged to pass between said rear supports and the 85 end walls of said cabinet, said latter supports having slots in their sides for engaging the ends of the filing rods.

AMANDUS KLITSCHE.
